FIG. 2.

FIG. 1.

FIG. 3.

NEAL T. MCKEE. INVENTOR.

BY
O. V. Thiele
ATTORNEY.

UNITED STATES PATENT OFFICE.

NEAL T. MCKEE, OF BRONXVILLE, NEW YORK.

LOCOMOTIVE.

Application filed February 14, 1925. Serial No. 9,337.

My invention relates to exhaust pipes for locomotives and has particular reference to the disposition of the auxiliary blower nozzle with respect to the main exhaust pipe.

In the ordinary form of locomotive, the draft necessary to support the high combustion rates which are employed is obtained by discharging the exhaust steam from the main engine cylinders through a nozzle located directly beneath the smoke stack, in the smoke-box portion of the boiler. The necessary artificial draft can, however, be obtained from this source only when the engine is in operation, and in order to produce a draft when the locomotive is standing idle or is drifting, an auxiliary steam jet operated by live steam is usually provided, for use when exhaust steam is not available. This auxiliary jet or blower is placed beneath the smoke stack and may be either closely adjacent to or within the main exhaust pipe.

During periods when the main engine is in operation the exhaust steam therefrom creates a pressure within the exhaust pipe above that existing in the smoke-box, but during periods when the engine is not in operation and there is no pressure within the exhaust pipe, ashes, soot and other solid matter contained in the combustion gases in the smoke-box are free to enter the exhaust pipe. When the locomotive is standing idle this foreign matter may enter the exhaust pipe by gravity alone, and this condition is greatly aggravated when the locomotive is drifting or coming to a stop with the throttle closed. In the latter case the continued reciprocation of the engine pistons creates a partial vacuum in the exhaust passages and pipe, which draws a considerable quantity of foreign matter of an abrasive nature from the smoke-box through the exhaust passages into the valve chests and cylinders of the engine. This results in scoring of the cylinder and valve chest walls and other serious damage.

In order to obviate the damage resulting from this reversal of flow through the exhaust passages I provide auxiliary jets or blowers which in addition to creating the necessary draft when the engine is shut off will also create during these periods a positive steam pressure within the exhaust pipe and thereby prevent flow reversal therethrough.

In the accompanying drawings I have shown two forms of my invention as applied to the conventional form of locomotive smoke-box; Figure 1 being a somewhat diagrammatic view in elevation of the front end of a locomotive with the smoke-box front removed, a portion of the figure being broken away to show a section through the exhaust pipe; and Figure 2 being a section taken on the line 2-2 of Figure 1. Figure 3 is a fragmentary section of a view similar to Figure 1, showing a slightly modified form of blower.

Referring to Figure 1, the cylinder 1, valve chest 2, and exhaust passages 3, are incorporated in the usual saddle casting 4. The exhaust passages 3 terminate closely adjacent each other in the bottom of the smoke-box 5. The exhaust pipe 6 is suitably mounted over the end of the passages 3 and carries at its upper end the jet forming nozzle 7, which should be directly beneath the extension 8 of the smoke stack. In order to bring the tip of the nozzle directly beneath the smoke stack it is sometimes necessary to offset the nozzle casting 6 longitudinally of the smoke-box and when this is done a deflecting web 9 is provided within the exhaust pipe casting 6 to direct the exhaust steam in a line parallel with the axis of the pipe.

According to this embodiment of my invention, the lower portion of the transverse web 9 is cored out to provide a narrow passage 10, which communicates with the longitudinal passage 11 provided in the central upper portion of the web 9, the passage 11 carrying the jet forming tip 12 at its upper end. It is of course to be understood that the upwardly directed jet may issue directly from the passage 11 and the web 9 may be omitted in cases where the exhaust pipe 6 is vertical, although the web may be useful in any case as a support for the passage 11. In the bottom of the passage 10 there are provided small ports 13 which serve to place this passage in direct communication with the main exhaust passages 3.

Pipes 14 connect the passage 10 with the steam space of the boiler, there being a valve 105 (not shown) located in the steam line, which is manually controllable from the locomotive cab, in order that the auxiliary or blower jet 12 may be operated as desired when the main throttle is closed, and shut 110

off when the main engine provides the necessary exhaust steam. If desired, the operation of the blower may be made automatic by known means forming no part of the present invention.

It is particularly to be noted that in my invention the blower tip 12 is placed well below the discharge end of the main exhaust nozzle 7 and in such relation thereto that when the blower nozzle is in operation the expanding jet of steam issuing therefrom completely fills the upper portion of the main exhaust pipe, issuing from the latter in the form of a jet which completely fills the opening in the nozzle.

This auxiliary jet aided by the jets issuing from the openings or ports 13 creates a pressure in the exhaust passages and the main exhaust nozzle which prevents the entrance of combustion gases and foreign matter such as ash, cinders, etc., into these passages under the influence of suction created in the main engine cylinders by the idly moving pistons.

It will be apparent that the number and exact disposition of the openings 13 will be subject to considerable variation with different engine designs, and in Fig. 3 I have shown a variation in which additional ports 13' are disposed both at the top and sides of the transverse passage 10' as well as at the bottom thereof.

The invention accomplishes the desired result by arranging the openings from the blower apparatus as a whole so that when the blower is in operation steam under a positive pressure is admitted to the exhaust passages, valve chests and cylinders of the engine, thereby substantially eliminating the suction normally produced by the engine pistons and preventing the possibility of impurities being drawn through the upwardly directed blower jet which, simultaneously with the creation of a pressure within the exhaust passages and pipe, fills the exhaust nozzle with an upwardly directed jet of steam.

What I claim is:

1. In a locomotive smokebox, the combination, with exhaust steam passages terminating in a main exhaust pipe; of auxiliary draft creating means located within said pipe, and means for supplying steam to said draft creating means, said first named means having discharge openings therein so located that when steam is supplied thereto a por-

tion of said steam is admitted to said main exhaust pipe and passages.

2. In a locomotive smokebox, the combination, with a main exhaust pipe; of a blower pipe located therein, said blower pipe comprising an upwardly directed discharge tip terminating below the upper end of said exhaust pipe and a plurality of discharge openings located below said upwardly directed tip.

3. In a locomotive smokebox, the combination, with a main exhaust pipe; of a blower pipe located therein, said blower pipe comprising an upwardly directed discharge tip terminating below the upper end of said exhaust pipe and a downwardly directed discharge opening located below said upwardly directed tip.

4. In a locomotive smokebox, the combination of an exhaust pipe, a transverse passage extending through said pipe, a longitudinal passage located within said pipe communicating at one end with said transverse passage and terminating in a discharge tip at its other end, said tip being below the upper end of said exhaust pipe, and a plurality of discharge openings in said transverse passage.

5. In a locomotive smokebox, the combination of an exhaust pipe, a transverse passage extending through said pipe, a longitudinal passage located within said pipe communicating at one end with said transverse passage and terminating in a discharge tip at its other end, said tip being below the upper end of said exhaust pipe, and a plurality of downwardly directed openings in said transverse passage.

6. In a locomotive, the combination with cylinder saddles having exhaust passages therein; of an exhaust pipe mounted over said passages, and a blower pipe located within said exhaust pipe, said blower pipe having an upwardly directed discharge tip located below the upper end of said exhaust pipe and a plurality of downwardly directed openings adapted to discharge into said exhaust passages.

7. In a locomotive smokebox, the combination with a main exhaust pipe, of a blower pipe located therein, said blower pipe comprising an upwardly directed discharge tip terminating below the upper end of said exhaust pipe, and a discharge opening located below said upwardly directed tip.

NEAL T. MCKEE.
